O. DALE,
PROCESS OF PRODUCING WOUND STRIPS OR TAPE OF VARNISHED FABRIC.
APPLICATION FILED AUG. 8, 1917.

Patented July 30, 1918.

UNITED STATES PATENT OFFICE.

OSWALD DALE, OF IRVINGTON, NEW JERSEY.

PROCESS OF PRODUCING WOUND STRIPS OR TAPE OF VARNISHED FABRIC.

1,274,144.

Specification of Letters Patent. Patented July 30, 1918.

Application filed August 8, 1917. Serial No. 185,167.

To all whom it may concern:

Be it known that I, OSWALD DALE, a citizen of the United States, residing at Irvington, in the county of Essex and State of New Jersey, have invented certain new and useful Improvements in Processes of Producing Wound Strips or Tape of Varnished Fabric; and I do hereby declare the following to be a full, clear, and exact description of the invention, such as will enable others skilled in the art to which it appertains to make and use the same.

My invention relates to the process of producing wound rolls of insulating tape or the like.

In the manufacture of insulation of this character, the practice is to first immerse a long web of fibrous material, such as fabric, in a solution of suitable insulating substance, 20 as varnish, which is subsequently oxidized and becomes a veritable component part of the fabric. The web may be treated with one or more coatings of the insulating substance, according to the particular requirements. A 25 bolt of fabric so prepared is placed on a cutting and winding machine in order that the web may be cut into a plurality of strips and these strips then wound into individual rolls of a size suitable for delivery to the trade. The cutting and winding machine usually employed for this purpose has a 30 part thereof, a tensioning device which is designed to maintain all of the strips taut as they are cut from the bolt of webbing, so that the individual rolls of the strips will 35 when the winding operation is completed, be in compact form and devoid of any tendency to come unwound. It has been found, however, that the tensioning device to which 40 reference has just been made will not impose a uniform tension on all of the individual strips at the same time because of the variance in the tensile strength of the fabric. Consequently, while some of the rolls will 45 be wound compactly, others will be wound loosely, and since it is essential that all of the rolls should be wound compactly and tightly, the loose rolls, when removed from the machine, have to be rewound entirely by 50 hand. This manual rewinding of the tape requires a great deal of time and is, therefore, a considerable item of expense in a plant where a large number of such machines are used.

55 I overcome this inherent disadvantage by the application of heat to the coated web-

bing at some convenient point in its length. Heat softens the insulating substance and renders it tacky, whereby the layers of the strips are caused to adhere to each other and 60 form compact rolls. This advantageous result obtains despite any slight variation in the operation of the tensioning device.

One way in which my invention may be carried out is shown in the accompanying 65 drawings, hereinafter described and embraced within the scope of the appended claims.

In said drawings,

Figure 1 is a side elevation of a cutting 70 and winding machine embodying my attachment,

Fig. 2 is a front elevation of the machine, partly broken away to more clearly show the position of the cutting disk, and 75

Fig. 3 is a detail sectional view of the heating unit.

Referring more particularly to the drawings, for a detailed description of my invention, numeral 1 designates generally a bed 80 comprising two side members or frames 2 which may be spaced any suitable distance. Bearings, as 3, the tension of which is regulable, are provided at the rear of the bed for receiving a shaft 4, around which is 85 wound a bolt of fabric 5. The web 6 of which this bolt is formed, and which it will be understood has been previously treated with a coating bath, is fed over the idler 7 and between shafts 8 and 9 carrying opposed 90 cutting disks 8' and 9' by means of which it is cut into strips 10, of any desired width. A certain number of these strips then pass forwardly under a heating roller 11 while the remaining strips pass under the heating 95 roller 12, and these different sets of strips are wound upon the rollers 13 and 14 respectively. If desired, an idler as 15, may be interposed between the cutting disk and the upper roller 13. Furthermore, tubes of 100 cardboard or other suitable material, as 16, may be detachably mounted on the rollers 13 and 14 to serve as cores for the several rolls.

The heating roller may be of any approved type. In Fig. 3 of the drawings, I have shown an electrical heating element 17, although I wish it understood that I may employ any equivalent form of heating device.

The heating of the coated fabric, in addition to rendering the coating tacky for the

purpose of causing successive layers of the fabric to adhere to each other, makes the fabric extremely pliable so that each of the successive layers of the roll will conform to each other to a nicety.

What is claimed is:

The herein described process, which consists in unwinding from one roll a web of fibrous material having a coating adapted to

be softened by heat, cutting said web into strips, winding said strips on to a roll, and in heating the material between the rolls to soften the coating and thus cause the successive layers of the second roll to slightly adhere to each other, but permit of their ready detachability.

In testimony whereof I affix my signature.
OSWALD DALE.
